DESIGN.

—o—

C. E. HAVILAND.

ORNAMENTATION OF DISHES.

No. 17,068.

Patented Jan. 18, 1887.

UNITED STATES PATENT OFFICE.

CHARLES EDWARD HAVILAND, OF LIMOGES, FRANCE.

DESIGN FOR THE ORNAMENTATION OF DISHES.

SPECIFICATION forming part of Design No. 17,068, dated January 18, 1867.

Application filed November 20, 1866. Serial No. 219,525. Term of patent 14 years.

To all whom it may concern:

Be it known that I, CHARLES EDWARD HAVILAND, a citizen of the United States, residing at the city of Limoges, in the Republic of France, have invented and produced a new and original Design for Dishes, which is described and fully represented in the following specification and accompanying fac-simile, forming a part of the same.

10 The accompanying fac-simile illustrates, as one of the many dishes to which the design is applicable, a perspective view of a plate embodying the design.

15 The characteristic feature of this design is the ornamentation produced by skeleton representations of wild roses in full bloom and arranged in a multifarious group. This grouping may cover the entire surface of the dish

or only a portion of the same, and may in either case have associated with it other ornamental embellishments without altering its characteristic features—*e. g.*, the embossed pattern A, the sprays of roses B, and similar ornamentation.

What is claimed is—

20 The design for the ornamentation of dishes, the same consisting of skeleton representations of wild roses multifariously grouped, substantially as shown and described.

25 In testimony whereof I have hereunto set my hand in the presence of two subscribing witnesses.

CH. ED. HAVILAND.

Witnesses:

F. CATE,
A. SENÉQUE.
